UNITED STATES PATENT OFFICE.

HERBERT C. PAWSON, OF TORONTO, ONTARIO, CANADA, ASSIGNOR OF ONE-HALF TO
ELIAS E. SLAGHT AND SAMUEL L. SQUIRE, BOTH OF TORONTO, CANADA.

BOILER IMPROVER AND FUEL ECONOMIZER.

Application filed August 4, 1925. Serial No. 48,135.

This invention relates to boiler improvers and fuel economizers of the type in which fresh air is admitted into the combustion chamber of the boiler for the purpose of promoting combustion of unconsumed flue gases, and my object is to devise a construction by means of which the efficiency of the boiler may be considerably increased relative to the amount of fuel consumed and which may be constructed with a minimum of machine work whereby the cost of production is kept down to a minimum.

I attain my object by means of the constructions hereinafter described and illustrated in the accompanying drawings in which—

Fig. 1 is a longitudinal section of a brick set boiler and furnace showing my improved device in position;

Fig. 2 a vertical section of my device on a larger scale; and

Fig. 3 a cross section on the line 3—3 in Fig. 2.

In the drawings like numerals of reference indicate corresponding parts in the different figures.

1 is the brick setting of a boiler and furnace of ordinary type. In the rear wall, preferably at or about the level of the lower side of the boiler 2, is formed a rectangular opening in which is fitted the closed rectangular casing 3 of suitable metal. The outer end 4 of the casing is formed as a removable cover and is provided with at each side a pivoted latch 5 adapted to engage the projections 6 inside the casing. When the cover is in position and these latches engaged, they cannot be disengaged except by the introduction of a suitable tool through the opening 7. The probability of the device being interfered with by incompetent or unauthorized persons is thus minimized as the user will seldom be aware of the precise nature of the lock employed.

45 An L-tube 8 is screwed into the opening 7 forming an air inlet for the device. At the opposite end an elongated air outlet opening 9 is provided, preferably opposite the opening 7. Adjacent the inner end, but 50 spaced therefrom, is formed a diaphragm 10 which has openings 11 formed therein at its side remote from the outlet 9. In the casing are located a plurality of baffles 12, and these baffles are all precisely similar 55 and each one provided adjacent one edge

with an opening 13. When in position these baffles are positioned so that the openings 13 are alternately at opposite sides of the casing so that a zigzag passage is formed for the air entering the inlet opening 7. In practice all the openings, including the inlet and outlet openings, are located at the top or bottom of the casing. Each baffle is provided with a plurality of rows of spaced fingers 14, preferably frustoconical in form. These fingers serve to space the baffles from one another and from the diaphragm 10 so that the interior of the casing may be left smooth and free of projections. These baffles are positioned by dropping them one after the other into the casing with the openings 13 in the proper positions. The latches 5 are locked to prevent outward displacement of the outer baffle 12. These fingers become heated by conduction from the inner end of the casing, which is exposed to the flue gases, forming effective means for transferring heat to the incoming cold air so that the air is sufficiently warmed before passing in to mix with the flue gases in the combustion chamber of the furnace. The upper row of fingers 14 on the baffle 12 nearest the diaphragm 10 are somewhat shorter than the others so as not to interfere with the passage of air through the openings 11 and the lower and upper rows of fingers of alternate baffles opposite the openings 13 are also slightly shorter.

I find with my device that the efficiency of the heating system is much increased relative to the amount of fuel burned, so much so that in some cases where the efficiency of the system has not been up to the required rating, by the use of my device it is possible to so increase the efficiency as to render the installation of a larger boiler unnecessary. The heat is held more steady and uniform, better combustion of the fuel is obtained leaving only a fine ash, and greater time may be taken between firing periods.

The device, it will be noted, is very compact and simple to manufacture and install.

What I claim is:—

1. A boiler improver and fuel economizer comprising a rectangular casing adapted to be inserted in an opening in the rear wall of a boiler setting and having a transversely arranged air outlet at the lower side of its

inner end; a removable closure for its outer end having an air inlet therein; an upright diaphragm located in and integral with the casing adjacent to but spaced from said inner end and having a plurality of small holes therein remote from the air outlet; and a plurality of baffles fitted within the casing to form a zig-zag passageway for the air and removable through the outer end of the casing.

2. A boiler improver and fuel economizer comprising a rectangular casing adapted to be inserted in an opening in the rear wall of a boiler setting and having a transversely arranged air outlet at the lower side of its inner end formed with an inclined lower edge; a removable closure for its outer end having an air inlet therein; an upright diaphragm located in and integral with the casing adjacent to but spaced from said inner end and having a plurality of small holes therein remote from the air outlet; and a plurality of baffles fitted within the casing

to form a zig-zag passageway for the air and removable through the outer end of the casing.

3. A boiler improver and fuel economizer comprising a rectangular casing adapted to be inserted in an opening in the rear wall of a boiler setting and having a transversely arranged air outlet at the lower side of its inner end; a removable closure for its outer end having an air inlet therein at its lower side opposite the air outlet; an upright diaphragm located in and integral with the casing adjacent to but spaced from said inner end and having a plurality of small holes therein remote from the air outlet; and a plurality of baffles fitted within the casing to form a zig-zag passageway for the air and removable through the outer end of the casing.

Signed at Toronto, Canada, this 25th day of July, 1925.

HERBERT C. PAWSON.
